By his Attorney.
W. B. H. Dow.

UNITED STATES PATENT OFFICE.

EDWARD F. GOODWIN, OF TAUNTON, MASSACHUSETTS, ASSIGNOR TO
EDWARD F. GOODWIN, TRUSTEE, OF SAME PLACE.

TAG-HOLDER.

SPECIFICATION forming part of Letters Patent No. 383,523, dated May 29, 1888.

Application filed December 12, 1887. Serial No. 257,607. (No model.)

To all whom it may concern:

Be it known that I, EDWARD F. GOODWIN, a citizen of the United States, residing at Taunton, in the county of Bristol and Common-
wealth of Massachusetts, have invented cer-
tain new and useful Improvements in Tag-
Holders, of which the following is a specifica-
tion.

My invention consists of a convenient tag-
holder to be attached to mail-pouches, trunks,
and various articles, means being provided
for holding the tag securely in place and for
easily introducing and removing the same.

Figure 1 of the drawings is a plan view of
my improved tag-holder closed, with the tag
in place. Fig. 2 is a plan view of the same
open, with the tag removed. Fig. 3 is a side
view of the holder when closed; and Fig. 4 is a section through the center, the tag being in-
serted and the cover half-open.

A is the card-receiving frame, firmly secured
to the plain base-plate B, which is attached to
the mail-pouch or other article in any desired
manner. The rear end of the receiving-frame
25 A has two projecting portions, d d, which are
rounded over the hinge-bolt C.

C is the cover, hinged at one end to the re-
ceiving-frame, as shown, preferably, by having
its end e bent around the hinge-bolt C'. The
30 spring p, secured to the inner surface of the
base-plate B in any desired manner, as by the
rivet a, bears at its free end p² against the end
e of the hinged cover C, which is squared off
along the portion of its width directly over
35 the spring p², as clearly shown in the draw-
ings. An aperture, b, is made in the base-
plate B directly below the hinge, thereby al-
lowing the spring p² to bend downward when
the cover C is raised. This spring, pressing
40 upon the squared-off surfaces of the portion e
of the cover, holds the cover firmly in place
when open or closed and tends to keep it in
either one or the other of those positions. The
cover C has an opening around the printed
45 portion of the tag, and when closed retains
the tag securely in the receiving-frame A.

E is a thin bar, preferably flush with the
upper surface of the receiving-frame and set
securely therein, under which the end of the

tag D easily slips and is held down as best 50
shown in Fig. 4. The spring p is forked at its
outer end, p', and bent upward, so as to bear
with a light pressure upon the card D, so that
when the cover is opened one end of the said
card is automatically raised and presented for 55
removal, the other end being still held under
the thin retaining-bar E. This pressure, how-
ever, is extremely light, so that the end p² of
the spring p is sufficiently powerful to hold
the cover firmly closed against the upward 60
pressure of the forked end p', or a separate
spring from that used to operate the hinged
cover may obviously be employed to raise the
tag for removal.

I claim—

1. A tag-holder consisting of the combina-
tion of a card-receiving frame, a cover, C,
hinged to one end thereof, said frame being
provided with a retaining-bar, E, near the
hinged end, a base-plate, B, and a spring, p', 70
secured to said plate and bearing against the
card, whereby when the cover is raised one
end of the card is automatically thrown up,
substantially as described.

2. A tag-holder consisting of a card-receiving frame and a retaining-cover hinged thereto, 75
said frame being provided with a spring, free
at both ends, attached to said frame, whereby
one end of the spring bears against the hinged
end of the cover and the other end of the
80 spring against the card, substantially as and
for the purposes described.

3. A tag holder consisting of a card-receiving frame, A, having a plain base-plate, B,
provided with an aperture, b, a cover, C, 85
hinged at e to the plate B, and a spring, p,
free at both ends, secured at a point interme-
diate of its ends to the said plate B, whereby
one end of the spring works against the cover
and the other end of the spring against the 90
card, substantially as described.

In witness whereof I have hereunto set my
hand.

EDWARD F. GOODWIN.
